UNITED STATES PATENT OFFICE.

ALBERT E. VOGT, OF ROCHESTER, NEW YORK, ASSIGNOR TO EMERGENCY RUBBER COMPANY,
OF ROCHESTER, NEW YORK, A CORPORATION OF NEW YORK.

DESIGN FOR A PURSE OR BAG.

No. 38,919.

Specification for Design

Patented Dec. 3, 1907.

Application filed October 7, 1907. Serial No. 396,354. Term of patent 7 years.

To all whom it may concern:

Be it known that I, ALBERT E. VOGT, a citizen of the United States, residing at Rochester, in the county of Monroe and State of New York, have invented a new, original, and ornamental Design for a Purse or Bag, of which the following is a specification, reference being had to the accompanying drawing, wherein,

I claim:

The ornamental design for a purse or bag as shown.

ALBERT E. VOGT.
